UNITED STATES PATENT OFFICE.

CLAUS E. ERICKSON, OF DES MOINES, IOWA.

DESIGN FOR A SERVICE HOLDER FOR ICE PICKS AND BOOKS.

Application filed April 17, 1922. Serial No. 1,812. Term of patent 7 years.

To all whom it may concern:

Be it known that I, CLAUS E. ERICKSON, a citizen of the United States, and a resident of Des Moines, in the county of Polk and State of Iowa, have invented a certain new, original, and ornamental Design for a Service Holder for Ice Picks and Books, of which the following is a specification, reference being had to the accompanying drawing, forming part thereof.

I claim:

The ornamental design for a service holder for ice picks and books, as shown. Des Moines, Iowa, April 12, 1922.

CLAUS E. ERICKSON.
